(57) **CLAIM**

The ornamental design for a display panel or portion thereof
with graphical user interface, as shown and described.

DESCRIPTION

This patent or application file contains at least one drawing
executed in color. Copies of this patent or patent application
publication with color drawing(s) will be provided by the
Office upon request and payment of the necessary fee.

The FIGURE is a front view of a display panel or portion
thereof with graphical user interface according to our new
design.

The broken lines illustrate the display panel or portion
thereof and form no part of the claimed design.

**1 Claim, 1 Drawing Sheet
